Patented Nov. 30, 1915.

UNITED STATES PATENT OFFICE.

SERGIUS P. GRACE AND RICHARD A. L. SNYDER, OF PITTSBURGH, PENNSYLVANIA.

TELEPHONE-RECEIVER.

1,161,856.

Specification of Letters Patent. Patented Nov. 30, 1915.

Application filed October 17, 1910. Serial No. 587,373.

To all whom it may concern:

Be it known that we, SERGIUS P. GRACE and RICHARD A. L. SNYDER, citizens of the United States, residing at Pittsburgh, in the State of Pennsylvania, have invented a new and useful Improvement in Telephone-
receivers, of which the following is a full, clear, concise, and exact description.

Our invention relates in general to apparatus for transforming electric waves into mechanical vibration, and more particularly to a loud speaking telephone receiver; its object is to simplify and improve the construction of such apparatus, whereby great efficiency is secured.

An ordinary type of telephone receiver comprises as its principal elements an electro-magnet, a diaphragm, and a permanent magnet, the diaphragm being supported in close proximity to one of the poles of the electro-magnet, and the permanent magnet creating the initial magnetic field in the air gap between the pole and the diaphragm. This initial magnetic field is then caused to be varied by and in accordance with the voice currents flowing in the coil of the electro-magnet, the diaphragm being caused to vibrate by the variable attractive force which is exerted directly upon it through the air gap, and thus producing sound waves, which follow closely the undulations of the voice currents. Although it is usual to employ a permanent magnet for the purpose of developing the initial magnetic field, an electro-magnet may be employed for the same purpose; or a single electro-magnet may be employed, the coil of which receives a steady flow of current which creates the initial field and also receives the voice currents superposed on the steady current.

The general type of telephone receiver to which our invention particularly relates, differs from this ordinary type principally in having the diaphragm placed away from the pole or poles of the electro-magnet, the diaphragm however being connected to an armature by a lever which communicates the movements of the armature to the diaphragm. The armature is made heavier than the ordinary receiver diaphragm; consequently the vibratory movements of the armature due to the voice currents in the coil of the electro-magnet are of small amplitude, the object of the connect-

ing lever being to multiply the movement of the armature in the diaphragm. The armature, being of heavier mass than it is possible to make the diaphragm, is however acted upon by the electro-magnet with greater force, and the net result is that a greater movement is imparted to the diaphragm than is possible where the diaphragm is directly acted upon as in the case of the ordinary telephone receiver.

A telephone receiver constructed in accordance with our invention, is provided with an armature mounted on bearings lying approximately in line with its center of gravity. Each end of the armature lies in proximity to one of the pole pieces of a two coil electro-magnet, and an initial magnetizing force is provided for which polarizes the two pole pieces alike. The electro-magnet is preferably of the horse-shoe type, the armature being pivoted midway between the free poles thereof and the two ends of the armature lying close to said poles. The initial magnetizing force for the armature is generated by a magnet, which may be either permanent or electro, one pole of this magnet being presented to the yoke of the electro-magnet, and the other to the armature midway between its ends and thus directly over its bearing. By this construction, an equal normal attractive force between the free ends of the armature and the free poles of the electro-magnet is secured. In order that the armature may be held in stable equilibrium, a pair of springs, preferably adjustable, may be arranged to bear against the armature on either side of its pivotal bearing.

Our invention will be better understood by a reference to the accompanying drawing in which—

Figure 1 is a side elevation partly in section of a loud speaking telephone receiver, together with a diagram of circuits suitable for controlling its operation; and Fig. 2 is an end elevation of the structure with a part broken away to show the bearing of the armature.

Referring to the drawing, the receiver comprises as its principal elements a normal energizing or polarizing magnet 1, an operating electro-magnet 2, an armature 3, and a diaphragm 4. The armature is pivoted or fulcrumed on a pivotal axis 5 of steel

on bearing pins 6 6 also of steel set in the sides of the brass frame 7. It will be noted that the axis of movement of the armature lies approximately through its center of gravity. The armature is held in place by springs 8 which bear against the outer surface thereof, and which hold the armature firmly against the knife edge bearings between the axis 5 and pins 6, as shown in Fig. 2, where the frame is broken away. The springs 8 are capable of being adjusted by turning the screws 9 9 so that the armature may be caused to take a position in which the air gaps between its ends and the pole pieces 10 11 of the electro-magnet are approximately equal; preferably the armature is built up of laminated iron and it is rigidly connected by a very light but stiff arm 12 to the center of the diaphragm 4, the outer end of this arm being secured to the diaphragm by a small screw 13. As the mass of the armature is an element controlling the pull of an electro-magnet thereon, it is desirable to employ a comparatively large armature and to employ springs to overcome the inertia of the armature and the parts operated thereby in return to normal position. By the use of a construction, the armature and diaphragm may be given a vibratory movement corresponding to the frequency of sound waves.

The diaphragm may be held in any suitable manner. As shown it is secured in a cupped part 14 of the frame and held in place between gaskets 15 by a cap 16. This cap has an orifice provided with a horn 17, the outer end of which is supported by a forked plate 18 fastened to the base of the frame by screws 19. The diaphragm is preferably of mica and preferably is so mounted that it lies in a plane which passes through the axis of movement of the armature, the object being to permit free movement of the diaphragm. In order to obtain very light weight without sacrificing rigidity, the arm 12 is preferably tapered away from the armature.

Heretofore diaphragms have been operated by the armature of electromagnets, but the connection between the diaphragm and the armature has been angular, and the diaphragm will have, in addition to the movement corresponding to those of the armature, an added movement; in other words, the movements of the diaphragm will not correspond exactly to those of the armature. In the construction shown and described herein, the armature and diaphragm are so arranged relative one to the other, *i. e.*, the diaphragm in plane parallel with and passing through the axis of movement of the armature, and so connected that the movements of the armature will not be changed, modified, or added to in transmission to the diaphragm. The movements of the armature

and diaphragm vary only in amplitude, the latter being a greater distance from the common center of movement of both. As the arm extending from the armature to the diaphragm should be attached centrally to the latter, the arrangement of the diaphragm at an angle to a plane coinciding with the faces of the poles of the electro-magnet permits of a more compact arrangement of the parts and a simpler form of arm.

The operating electro-magnet 2, comprises a yoke 20 and two cores surrounded by the coils 21 22. It is held in place in the frame by screws 23 by which its position may be adjusted. The energizing magnet 1 may if desired be provided as shown with coils 24, which would be included in a local circuit. One of the poles 25 of this magnet extends underneath the yoke 20 of the electro-magnet 2, while the other pole 26 extends over the armature 3. The magnet 1 is adjustably secured to the frame by clamping plates 44 and screws 45. The normal magnetic circuit extends from pole 25 of magnet 1 to yoke 20 and through two cores of the electro-magnet in parallel to the poles 10 and 11, the armature 3, and from either end thereof to the middle and thence to the other pole 26 of electro-magnet 1.

The coils 21 22 of electro-magnet 2 may be included in a circuit 27 extending to an induction coil 28 and thence by way of circuit 29 to a second induction coil 30, the primary winding 31 of which, is included in a local circuit with a transmitting telephone 32 and a battery 33. This induction coil 30 may have one or more secondary windings. In the system of circuits shown there are two secondary windings, one of which, 34, is included in the circuit 29 referred to and the other of which, 35, is included in a circuit 36, which may be extended to a telephone repeater 37, the local circuit 38 of which includes a battery 39 and one winding of an induction coil 40. The other winding of this induction coil is included in a circuit 41 leading to another loud speaking receiver 42. There may be, as shown, a condenser 43 included in this last mentioned circuit.

The transmitting telephone 32, in the commercial use of the system would be located at a central station, while the loud speaking receivers would be located at various stations more or less at a distance from the transmitting station. Where the distance is great, the arrangement of circuits leading to the receiver 42 would be preferable, wherein the telephone repeater 37 assists to increase the volume of current in the receiver. At shorter distances, such telephone repeater would not be needed.

The operation is as follows: A person talking into the transmitting telephone 32

will cause voice current to traverse the circuits leading to the coils 21 22 of the loud speaking receivers at the various outlying stations. At any given moment when current is flowing in these coils, there is an increase in the attractive force at one pole, say pole 10, and a corresponding decrease in the attractive force at the other pole 11. The effect on the armature is thus to rotate it on its pivotal bearing in the direction of the hand of a clock and the diaphragm 4 is moved or bowed out slightly to the right in Fig. 1. At the next instant of time, the current reversing itself in the circuit, the attractive forces at pole 10 is decreased and at the pole 11 increased so that the opposite effect is had in the armature, and the diaphragm 4 is forced to move in the opposite direction. Every movement of the armature, however slight, is thus reproduced in the diaphragm, and is also multiplied by reason of the leverage exerted through the connecting arm 12. The armature being pivoted at its center and subject to the joint action of the poles 10 11 of the electro-magnet 2, exerted at its two ends, the inertia of the armature is reduced to a minimum and the power exerted therein to a maximum. The arm 12 and diaphragm 4 are very light and thus offer slight resistance to the movement, so that a very powerful effect is produced and the voice currents in the circuit are transformed into sound waves that are carried through the horn 17 and may be heard clearly at a considerable distance from the instrument.

Ideal conditions would be attained were it possible to provide an armature of large mass to permit a large flow of magnetic flux therethrough, but without weight, thus avoiding loss due to overcoming inertia. As such ideal conditions are impossible, an approximation thereto is obtained by so pivoting the armature as to be practically in equilibrium and its ends are simultaneously acted on by magnetic forces operating in opposite directions.

Having thus described our invention, we claim as new and desire to secure by Letters Patent the following:

1. In a telephone receiver, the combination of means for forming a magnetic circuit, an electro-magnet having its cores lying in said circuit and normally having the polarity of one of the members of said means, and an armature for said cores having its pivotal support between its ends and so as to lie between the electro-magnet and the second member of the means producing the magnetic circuit, whereby as one end of the armature is drawn to one pole of the electro-magnet on the passage of a current through its coils, the other end of the armature will be attracted in the opposite direction toward said second member, and means

for connecting the armature to the receiver diaphragm.

2. In a telephone receiver, the combination of two separated magnetic poles of a magnet forming opposite polarity, an electro-magnet having its cores forming continuations of one of said poles, an armature lying between the ends of the cores and the free pole of the magnet and having a pivotal support intermediate its ends, the axis of movement of the armature being in a plane parallel with and intermediate the cores of the electro-magnet and also intermediate said magnetic poles whereby the ends of the armature are subjected simultaneously to oppositely acting forces, and means for connecting the armature to the receiver diaphragm.

3. In a telephone receiver, the combination of means for forming two separated magnetic poles of opposite polarity, an electro-magnet having its cores forming continuations of one of said poles, an armature placed between the cores and the free end of the pole forming means, and having a pivotal support intermediate its ends, the axis of movement of the armature being in a plane parallel with and intermediate the cores of the electro-magnet and also intermediate said magnetic poles whereby the ends of the armature are subjected simultaneously to oppositely acting forces, springs adapted to facilitate the responsive movements of the armature and means for connecting the armature to the receiver diaphragm.

4. In a telephone receiver, the combination of an electro-magnet having parallel axes and poles permanently magnetized to the same polarity, a polarized armature pivotally mounted in a plane passing between the poles of the magnet whereby the armature may be turned in one direction by one pole and in the opposite direction by the other pole and means for forming a magnetic pole of a polarity opposite that of the poles of the electro-magnet and placed on the side of the said armature opposite the electro-magnet and adapted to act in conjunction with the poles of the electro-magnet in shifting the armature by simultaneously attracting opposite ends of armatures in opposite directions, and means for connecting the armature to the receiver diaphragm.

5. In a telephone receiver, the combination of an electro-magnet having parallel axes and poles permanently magnetized to the same polarity, a polarized armature pivotally mounted in a plane passing between the poles of the magnet whereby the armature may be turned in one direction by one pole and in the opposite direction by the other pole, and means for forming a magnetic pole of a polarity opposite that of the

poles of the electro-magnet adapted to act in conjunction with the poles of the electro-magnet on the side of the armature opposite the electro-magnet in shifting the armature, 5 and a diaphragm connected to the armature and arranged in a plane passing through the axes of the armature.

In witness whereof we hereunto subscribe our names this 8th day of July, A. D. 1910.
